UNITED STATES PATENT OFFICE.

HAROLD EMERSON, OF CHARLESTOWN, MASSACHUSETTS.

REGULATOR EMPLOYED IN TEMPERATURE-REGULATING SYSTEMS CONTROLLED BY THERMOSTATS.

1,180,582.

Specification of Letters Patent.

Patented Apr. 25, 1916.

Application filed June 27, 1913. Serial No. 776,102.

To all whom it may concern:

Be it known that I, HAROLD EMERSON, a citizen of the United States, residing at Charlestown, in the county of Suffolk and 5 State of Massachusetts, have invented a new and useful Improvement in Regulators Employed in Temperature-Regulating Systems Controlled by Thermostats.

My invention resides particularly in electrically operated means that will through the agency of a local auxiliary sustaining circuit insure the positive opening or the closing of dampers located at the source of heat, under all conditions.

15 In the drawings illustrating the principle of my invention and the best mode now known to me of embodying the same in an operative structure, Figure 1 is a front elevation of a regulator with cover removed, 20 containing elements of my invention; Fig. 2, a vertical section, on line 1-2, Fig. 1; Fig. 3 is a vertical section of a preferred form 25 of thermostat to be used with my invention. Fig. 4 is a diagrammatic view of the mechanisms and the electric circuits employed. Fig. 5 is a perspective view of the damper actuating member, circuit closers and their contacting members in normal position.

30 A regulator, Figs. 1 and 2, embodying the features of my invention, hereby claimed, is inclosed in a metal case Q, which is located and fixed where required by means of a hanger H and a plate Q' that intermesh and 35 are secured as by pins and cotter pins c.

Within the case is an electric motor M M which furnishes the power of the regulator. On the motor shaft is a small spur gear G' which engages a large gear G on the shaft 40 R, Fig. 2, mounted in bearings T, B. To take care of the thrust of the shaft R, I provide the bearing T with a ball bearing comprising a ball b mounted in a cup member e, and retained there by a cap f fitted to the 45 member e and serving as one of the bearings for the shaft R. On the shaft R is a worm gear W whereby power may be transmitted to the driving gear D on the main shaft O, Fig. 1, mounted in suitable bushings d, d, in 50 the case Q.

Both ends of the main shaft O, Fig. 1, have cranks K which are connected in a well known manner, not here shown, by a system of chains and pulleys with front and 55 back dampers of the heating source.

Circuit closers C, C, Figs. 1 and 5, are mounted on the main shaft O, Fig. 1, and consist of two drums x'', x'', of insulating material, with semi-cylindrical brass pieces y'', y'', oppositely disposed and each having 60 an advancing rectangular portion removed. To engage these circuit closers C, C, are adjustable springs S¹, S², S³, S⁴, S⁵, S⁶, mounted at the top of the case and held in place by contact screws n. These circuit closers are designed to shift a thermostat starting circuit, later to be pointed out; and to close and open a local auxiliary sustaining circuit, also to be described hereinafter; the length of the removed portion of each 65 circuit closer being such that its respective brush as S¹ or S⁶ all but makes contact with that portion of the circuit closer under said brush, when crank member K is in one of its two opposite normal positions, as shown in 70 Fig. 5.

As to the relations between the circuit closers and the adjustable spring contact members, it is to be particularly noticed, First, that the distance between the contact 80 member S¹ (Fig. 5), and that portion y'' of the circuit closer beneath it, represented between the dotted lines a, b, (Fig. 5), is such that a brake A, (Fig. 4), to be fully explained hereinafter, will always have 85 brought the motor M M, and the operatively connected damper shaft O, and circuit closers thereon, to rest in normal position, before the said contact member S¹ and the circuit closer y'' can make contact. Second, 90 that that portion of the circuit closer y'' adjacent to the removed portion, is of such angular length that its contact members S², S³, have engaged it, previous to the cutting out of the other group of contacting members S⁴, S⁵, S⁶, on their circuit closer y''. Third, that the angular length of that part 95 of the circuit closer y'' under the thermostat starting contacting member S³, need be only of such length that the said contacting member, will remain in said contact only until after the auxiliary sustaining circuit contact member S¹ has made contact with its 100 said circuit closer y''.

Control magnet E, Fig. 1, is supported on 105 the side of the case. Its armature a is fixed to the free end portion of an arm A pivoted on a pin p, set in a shoulder S³, Fig. 2, on the motor frame. An extension of the arm A constitutes a brake arm having 110

- therein, a piece of friction producing material t which normally engages a friction wheel F , on the motor shaft, by reason of the weight of the arm A and the armature a .

5 Also mounted on the arm A , and insulated therefrom, is a platinum point P^2 designed to make contact with an adjustable platinum point P^1 directly above it, when the armature a is picked up by the magnet E .

10 A switch S for locally operating the dampers, is placed under the case.

Fig. 4 shows circuit plan. Thermostat Z , the preferred form of which is shown in Fig. 3, is connected with regulator through

15 a small three-wire cable. A source of power, as a step-down transformer T' , tapped on to a lighting circuit delivers a current of low voltage between t' and t^2 for a controlling circuit, and a current of higher voltage

20 between t' and t^3 for the motor circuit. As shown in Fig. 4, the control circuit has just been broken on left hand circuit closer C, C , and made on right circuit closer C, C . Crank K is in position for checking the fire.

25 As the temperature drops, tube Z is tipped to the left, by the contraction of spring Y , Fig. 3, and a thermostat starting circuit is completed through x and mercury z , Fig. 4. Current flows from t' to arm o of switch, to

30 l, z, x, r , spring S^4 , through y'' to S^5 to e' , through magnet E , and back to transformer t^2 . Magnet E is energized, motor brake A released, and motor circuit completed from t' , through motor, through contact point P'

35 to other side of transformer t^2 . Motor will begin, and continue to operate until crank K has completed a half revolution, and opened the drafts, at which point, control circuit is broken through the right hand circuit

40 closer C, C , and contacts are made on the left hand circuit closer C, C . Magnet E is deenergized, motor circuit is broken through the points P', p^2 , and the brake applied. The drafts being open, the temperature in-

45 creases. With the expansion of thermostat spring Y , tube Z tips to the right. When temperature corresponds to that indicated by the pointer, a thermostat starting circuit will be completed between y and z . Then the

50 said circuit will be completed from t' to o , to l , to z , to y , to spring S^3 , through y'' to S^2 (contact being made on the left circuit closer, and open on right) to e' , through coils E and back to transformer t^2 . Motor

55 will again operate and bring crank K to check position. Thus the drafts will open and close to maintain the temperature at which thermostat pointer p' , Fig. 3, is set.

As shown in Fig. 4, crank K is in check

60 position. Throwing switch S to the right establishes a circuit from t' to o , to r , to spring S^4 , through y'' to spring S^5 to e' , and through magnets E to t^2 , and motor M , operates to open drafts. Contacts

65 will now be broken on the right hand cir-

cuit closer C, C, and made on the left. Throwing switch to right cuts power off thermostat at point 1. Returning switch to normal left hand position reestablishes circuit from t' to o , to l , to z , to y , to spring S³ 70 through y'' (contact being now made on left circuit closer C, C) through spring S² to e' , through coils of magnet E, and back to t^2 . This last circuit is completed through points y and z . If thermostat circuit were making 75 through x and z , drafts would already be open, and there would be no necessity of throwing switch to the right, the object of switch being to open drafts when starting, or shaking down fire, when thermostat is 80 regulating to check fire, that is, when dampers are closed.

Now, were it not for the mechanism, the operation of which I will next describe, should the thermostat make intermittent contact for a considerable length of time, the crank would advance intermittently through quite a part of the whole arc of its travel, before the circuit through the thermostat would be permanently established; this constant starting and stopping thus increasing the wear and tear of the mechanism, and the noise of its operation becomes objectionable. And further, when using the switch for operating the regulator, if contact is made on right and then broken, there is a possibility of the crank arm assuming any position in the arc of its travel and stopping there. And still further, were the damper actuating member, and consequently the circuit closer y'' , manually moved ahead out of normal position clearly shown in Fig. 5, said member could not be returned to normal position until after the thermostat had completed a circuit through one of its legs, U or V.

I will proceed to show how the principal feature of my invention overcomes these objections.

In Fig. 4 suppose x and z to make contact intermittently. Then a thermostat starting circuit will be established through t' , o , l , z , x , r , S^4 , y'' , S^5 , e , E , t^2 and back to t' . When y'' on the right, advances enough to establish a contact with brush S^6 , then E will remain energized until stroke is completed through an auxiliary sustaining circuit t' , f'' , f' , S^6 , y'' , S^5 , e' , E , t^2 , t' , regardless of thermostat starting circuit. Contacting brush member S^1 is left in the same relative position to its circuit closer y'' , as brush S^6 was, before the above-mentioned action. That is, the left and right hand circuit closers C , C , are identical. Should y , z , make intermittent contact, then a thermostat starting circuit would be established from t' , o , l , z , y , S^3 , y'' , S^2 , e' , E , t^2 , and back to t' ; and when y'' advances enough to establish contact with its brush S^1 , then magnet E will remain energized.

until the stroke is completed, through the local auxiliary sustaining circuit t' , f'' , f' , S^1 , y'' , S^2 , e' , E , t^3 , t^2 , back to t' , regardless of the thermostat starting circuit through 5 y , z . If switch S is thrown to the right, and then left between points l and r , if duration of contact were sufficient to advance y'' to contact S^6 , then magnet E will remain energized, through local circuit t' , 10 f'' , f' , S^6 , y'' , S^2 , e' , E , t^2 , t' , until stroke is completed, although switch circuit is open. And if the damper actuating member K is, for example, manually advanced, and the thermostat starting circuit, at points x , z or 15 z , y , is open, and, since the return of member K to normal position, has not been completed either permanently or intermittently, and hence has not energized the motor magnet E , then said magnet (the damper actuating member being out of normal position) is at once energized by the auxiliary sustaining circuit, which, as before stated, is at once completed through say the contact member S^1 , and circuit closer y'' , or 20 through S^6 , and y'' , and remains energized until the end of the stroke of the member K . In short, any manual displacement of the damper actuating member, and hence the circuit closers, exceeding a predetermined 25 amount, will always result in a return of said member to normal position, because of a positive local supply of electrical current through the auxiliary sustaining circuit, other than through the points of the thermostat. In fine, I attain all of the herein-before results by making use of suitable means, and a local auxiliary sustaining circuit, independent of the thermostat starting circuit, or the switch circuit, so 30 designed that after the crank shaft has advanced a predetermined part of its whole travel, the magnet will become energized and remain so energized by the auxiliary sustaining circuit, during the rest of its 35 travel to a normal position.

Desiring to protect my invention in the broadest manner legally possible, what I claim is:

1. In an electric motor-driven regulator, 50 having damper actuating member operatively connected to said motor; a source of electrical energy; a motor circuit; an electro-magnet, whose armature opens and closes the motor circuit; a thermostat; a 55 thermostat starting circuit, the closing and opening of which by the thermostat energizes said electro-magnet:—a local auxiliary sustaining circuit, independent of the thermostat starting circuit, but including 60 said electro-magnet; circuit closing means in said auxiliary sustaining circuit; means actuated by said motor for closing said auxiliary sustaining circuit, only when the damper actuating member has been displaced 65 by a predetermined amount from a normal

position, and regardless of whether said displacement was or was not brought about by the completion of the thermostat starting circuit; all designed to insure the return of the damper actuating member to a 70 normal position, after having for any reason been displaced from a normal position.

2. In an electric motor-driven regulator, having damper actuating member; a source of electrical energy; a motor circuit; an electro-magnet, whose armature opens and closes the motor circuit; a thermostat; a thermostat starting circuit, but including said opening of which by the thermostat energizes said electro-magnet:—a local auxiliary sustaining circuit, independent of the thermostat starting circuit, but including said electro-magnet; circuit closing means in said auxiliary sustaining circuit; means actuated by said motor for closing said auxiliary sustaining circuit, said circuit closing means comprising twin rotary drum circuit closers mounted on said damper actuating member and insulated therefrom, similar in construction but oppositely disposed, each having an advanced portion removed; similarly disposed contacting members, one for each leg of the thermostat starting circuit; one for each circuit closer for the auxiliary sustaining circuit, and one for each circuit closer, for the purpose of forming a common return for both the thermostat starting circuit and for the auxiliary sustaining circuit, through the electro-magnet; the conducting portion of each circuit closer being 100 of such angular length, and so disposed with relation to its respective contacting member as to establish and maintain the thermostat circuit, throughout the alternate complete half revolutions of the damper actuating member.

3. A damper control regulator comprising a damper shaft provided with damper actuating devices; an electric motor; a motor circuit; a thermostat; a thermostat starting circuit; an electro-magnet for controlling the motor circuit; circuit closing members controlled by said damper shaft to open the live leg of the thermostat starting circuit after the completion of the half revolution, and to close the inactive leg of said thermostat starting circuit in preparation for the next move of the thermostat; an armature for said electro-magnet to close said motor circuit while the electro-magnet is energized; a local auxiliary sustaining circuit, independent of said motor circuit and said thermostat starting circuit, and embracing said electro-magnet; circuit closing members in said auxiliary starting circuit, 115 and controlled by said motor-driven damper shaft, for alternately completing said local auxiliary sustaining circuit through said electro-magnet, only after the motor-driven damper shaft has been moved a predetermined amount from a normal position.

- mined amount out of said normal position: all designed so that, should said damper shaft be out of normal position, and should the thermostat starting circuit have failed to energize the electro-magnet and start the motor, then the electro-magnet may be energized through the auxiliary sustaining circuit, to start the motor and cause the damper shaft to advance to a normal position.
- 13 4. A damper control regulator comprising a damper shaft provided with damper actuating devices; an electric motor; a motor circuit; a thermostat; thermostat starting circuit; an electro-magnet for controlling the motor circuit; circuit closing members controlled by said damper shaft to complete alternately through said electro-magnet, each of said thermostat circuits during a predetermined portion of each revolution
- 15 of the said damper shaft; an armature for said electro-magnet to close said motor circuit while the electro-magnet is energized;
- 20

a local auxiliary sustaining circuit, independent of said motor circuit and said thermostat starting circuit, and embracing said electro-magnet; circuit closing members in said auxiliary starting circuit, and controlled by said motor-driven damper shaft, for alternately completing said local auxiliary sustaining circuit through said electro-magnet, only after the motor-driven damper shaft has been moved out of said normal position, by the completion of the thermostat starting circuit; all designed so that when said damper shaft is out of normal position, the electro-magnet is energized through the auxiliary sustaining circuit, to cause the motor to move said damper shaft ahead from its advanced position and return to normal position. 25 30 35

Correction in Letters Patent No. 1,180,582.

It is hereby certified that in Letters Patent No. 1,180,582, granted April 25, 1916, upon the application of Harold Emerson, of Charlestown, Massachusetts, for an improvement in "Regulators Employed in Temperature-Regulating Systems Controlled by Thermostats," an error appears in the printed specification requiring correction as follows: Page 3, line 78, claim 2, for the words "but including said" read *the closing and*; and that the said Letters Patent should be read with this correction therein that the same may conform to the record of the case in the Patent Office.

Signed and sealed this 16th day of May, A. D., 1916.

[SEAL.]

J. T. NEWTON,

Acting Commissioner of Patents.
